TOY KITCHEN

Per O. Hoel, Plainsboro, Erkki Pekka Korpijaakkko,
Princeton, and Matthew A. Moustakas, Mercerville,
N.J., assignors to CBS Inc.

Filed Apr. 16, 1975, Ser. No. 561,224

Term of patent 14 years

Int. Cl. D21—01

U.S. Cl. D34—15 AC

The figure is a front perspective view of a toy kitchen showing my new design, the unshown sides being substantially plain and unornamented.

We claim:

The ornamental design for a toy kitchen, substantially as shown.
